UNITED STATES PATENT OFFICE

162,920

COMBINED RADIO-PHONOGRAPH AND TELEVISION CABINET

Samuel E. Adler, Chicago, Ill.

Application August 29, 1950, Serial No. 11,972

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combined Radio-Phonograph and Television Cabinet, of which the following is a specification, reference being had to the accompanying drawing, forming part thereof.

Fig. 1 is a perspective view of a combined radio-phonograph and television cabinet with the doors open, showing my new design;

Fig. 2 is a front elevational view thereof, the doors being shown closed; and

Fig. 3 is an end elevational view of the cabinet.

The dominant features of my design reside in the portions shown by full lines in the drawings.

I claim:

The ornamental design for a combined radio-phonograph and television cabinet, as shown and described.

SAMUEL E. ADLER.
